UNITED STATES PATENT OFFICE.

EMIL BENSON, OF JASPER, MINNESOTA.

DISH-DRAINER.

1,252,220.

Specification of Letters Patent. Patented Jan. 1, 1918.

Application filed July 27, 1916. Serial No. 111,713.

To all whom it may concern:

Be it known that I, EMIL BENSON, a citizen of the United States, residing at Jasper, in the county of Pipestone and State of Minnesota, have invented certain new and useful Improvements in Dish-Drainers, of which the following is a specification.

This invention contemplates an improved dish drainer and has as its primary object 10 to provide a device of this character which may be attached to any conventional type of dish pan or other similar vessel for supporting the dishes in position to drain the water therefrom back into the pan.

15 The invention has as a further object to provide a device of this character employing resiliently actuated catch members for connecting the drainer with the pan so that the drainer will be securely held in position.

20 And a still further object of the invention is to provide a drainer which will be simple in construction and may thus be produced at minimum cost.

25 Other and incidental objects will appear as the description proceeds and in the drawings wherein I have illustrated the preferred embodiment of the invention and wherein similar reference characters designate corresponding parts throughout the several 30 views:

Figure 1 is a top plan view showing my improved drainer applied to a conventional type of dish pan;

35 Fig. 2 is a sectional view more particularly showing the construction of the drainer, and illustrating the manner in which the drainer is connected with the pan,

40 Fig. 3 is a detail perspective view partly in section and illustrating the type of supporting brackets carried by the drainer for engagement with the top edge of the pan,

45 Fig. 4 is a similar view illustrating the type of resiliently actuated catch member carried by the drainer for engagement with the pan,

Fig. 5 is a sectional view showing a slightly modified form of the invention,

50 Fig. 6 is a detail perspective view partly in section and illustrating a modified form of catch member, and

Fig. 7 is a fragmentary perspective view showing a still further modification of the invention wherein the drainer is formed integral with a dish pan.

55 In carrying out the invention, the drainer is formed with an arcuate or semi-circular

body 10 outwardly flared toward its free edge and provided at its inner extremity with a foraminous draining flange 11 projecting upwardly and outwardly away from the body 10 so that the drainer is, as particularly shown in Fig. 2 of the drawings, substantially V-shaped in cross-section. The flange 11 is curved to conform to the longitudinal curvature of the body 10 and may 60 be integral therewith or secured to the body in any suitable manner. At its inner extremity, or adjacent the junction of the said flange with the body, the flange is provided with a series of drain openings 12. The 70 body 10 and flange 11 are flexible and preferably formed from suitable resilient sheet metal bent into desired shape. Extending downwardly from the outer side of the body 10 adjacent the inner extremity thereof, are 75 a plurality of circumferentially spaced supporting brackets 13. These brackets are each preferably formed from a strip of suitable sheet metal bent intermediate the ends thereof to define a substantially U-shaped 80 foot 14 with the extremities of the strip secured in any approved manner to the body 10. Adjacent its ends, the body of the drainer is provided with clips 15 having the working ends thereof presented downwardly and formed into hooks 16 with the said clips pivoted between ears 17 suitably connected to the body. Interposed between the body 10 and the clips 15, are springs 18, arranged to surround the pivot pins of the 90 said clips with the said springs normally acting to urge the working ends of the clips toward the body to active position.

The drainer thus described is formed to fit upon a dish pan or other similar vessel, 95 in the manner illustrated in Figs. 1 and 2 of the drawings. Such a pan is conventionally shown at 19 and is provided, at its free edge, with the usual flange 20. The body 10 is rested upon the flange to be supported by the brackets 13, the U-shaped feet 14 of which are adapted to embrace the flange 20 for holding the drainer against lateral displacement, while the hooks 16 of the clips 15 are engageable with the said 100 flange, as also illustrated in Fig. 2 for firmly connecting the drainer with the pan. When so attached to the pan, it will be observed that the drain openings 12 in the drain flange 11 are supported below the peripheral edge 110 of the pan. Dishes may accordingly be placed upon the body 10 to be supported by

the flange 11 when the water draining from the said dishes will run off through the openings 12 back into the pan. I accordingly provide a very simple and efficient construction for the purpose set forth and an arrangement wherein the presence of the drainer upon the dish pan will not interfere with the ordinary operation of washing the dishes. Attention is also directed to the 10 fact that by lengthening the bight portions of the feet 14 of the brackets 13, the said feet will thus be adapted to fit over the peripheries of pans of various diameters so that my improved drainer may thus be used 15 in connection with dish pans of various sizes. Furthermore, the drainer may be flexed, as indicated by dotted lines in Fig. 1, to adapt the drainer to different sized pans. When 20 so flexed, the drainer will, as will be clear, yieldably engage with the pan for tightly connecting the drainer therewith.

In Figs. 5 and 6 of the drawings, I have illustrated a slightly modified form of the invention which relates more particularly 25 to the construction of the draining flange employed as well as the type of attaching clip used to connect the drainer with the dish pan. In this modification, the body 10 of the drainer is provided with a foraminous 30 or reticulate draining flange 21 constructed of wire mesh and suitably secured to the body with the said flange arranged similarly to the flange 11 of the preferred form of the invention. In some instances, this arrangement may be found desirable. The 35 type of attaching clip used in connection with this modified form of the invention is shown in detail in Fig. 6. It will be observed that the said clip is formed from a 40 length of suitable resilient wire bent intermediate its ends to form a hook 22 with the extremities of the said wire then continued to provide springs 23 normally urging the free end of the clip toward the body 10 to 45 active position with the ends of the wire secured to the said body. One of these clips is arranged adjacent each end of the body 10 and is adapted to engage over the flange 19 of the pan in the manner best shown in 50 Fig. 5 for connecting the drainer with the pan. Otherwise, this modified construction is identical with the preferred form of the invention and a further description thereof is accordingly deemed unnecessary.

55 In Fig. 7 of the drawings, I have illus-

trated a still further modification of the invention wherein the drainer is formed integral with the dish pan. In this modification, the dish pan is indicated at 24 and may be of any approved type. Upon one side of 60 the pan, the circular wall thereof is, at its free margin, bent inwardly to define a draining flange 25 similar to the draining flange 11 of the preferred form of the invention and provided adjacent its inner extremity with drain openings 26. From the free outer edge of the flange 25, the metal of the pan is rebent upon itself and is then directed outwardly and upwardly to form the body 26 of the drainer similar to the 70 body 10 of the preferred form of the invention and adapted to receive dishes resting upon the draining flange 25. When so constructed, the drainer will form an integral part of the pan and, of course, the pan and 75 drainer may be produced from any approved material.

Having thus described my invention, what I claim and desire to secure by Letters Patent is:—

1. A dish drainer consisting of an arcuate body V-shaped in cross-section with its inner wall of relatively slight extent compared with its outer wall and formed with drainage openings, the body being adapted 85 for application to a dish pan with the base portion of its outer or more extensive wall engaging the edge of the pan whereby its bight portion is disposed just within the marginal wall of the pan and substantially 90 the entire pan is open to use, and means for supporting the body upon the pan.

2. A dish drainer consisting of an arcuate body V-shaped in cross-section with its inner wall of relatively slight extent compared with its outer wall, the body being adapted for application to a dish pan with the base portion of its outer or more extensive wall engaging the edge of the pan whereby its bight portion is disposed just 100 within the marginal wall of the pan and substantially the entire pan is open to use, the body being open at its ends and resilient whereby it may be sprung to engage the edges of pans of different diameters, and 105 means for securing the body to the edges of such pans.

In testimony whereof I affix my signature.

EMIL BENSON. [L.S.]
